UNITED STATES PATENT OFFICE.

GEORGE E. BRONSON, OF BEACON FALLS, CONNECTICUT, ASSIGNOR OF THIRTY PER CENT TO LEROY S. ANDREW, OF NAUGATUCK, CONNECTICUT.

COLLAPSIBLE FORM.

Application filed October 20, 1921. Serial No. 508,984.

To all whom it may concern:

Be it known that I, GEORGE E. BRONSON, a citizen of the United States, residing at Beacon Falls, county of New Haven, State 5 of Connecticut, have invented an Improvement in Collapsible Forms, of which the following is a specification.

This invention relates to collapsible forms and particularly to collapsible cores for ease 10 in casting tubes, although the principles of the invention are not confined to such use.

Heretofore, in casting metal tubes, the general practice has been to form a core of sand. The method generally employed is 15 to use a metal tube as a support for the sand and material forming the core. This tube is provided with securing means for the core material generally being drilled with a large number of holes to form this securing 20 means for the straw and supporting material for the sand. The operation of drilling the tubes, building up the core thereon, baking and finally removing them from the cast tubes is a long, slow and expensive 25 operation. Numerous attempts have been made to do away with the sand cores, but so far as I am aware, prior to my present invention none of them have been successful, as the castings were not uniform or 30 homogeneous, but contained numerous blow holes, and it was very difficult to remove the core from the casting after it had hardened.

It is, therefore, an object of my invention to provide a metal core for casting tubes and the like which will give a homogeneous product free from blow holes or "pits," and which does not require the use of sand and the usual core materials, so doing away with the labor necessary in forming such cores and the subsequent baking operation.

It is a further object of my invention to provide a core which may be easily and quickly removed from the casting, and which does not require rebuilding for a subsequent casting operation.

It is a still further object of my invention to provide a core which is simple in construction, comprising comparatively few parts which may be easily and quickly assembled and disassembled, and which will be much cheaper to manufacture than the old type of core.

With these and other objects in view I

have devised the core illustrated in the accompanying drawing in which, 55

Fig. 1 is a vertical, longitudinal section through a mold with my improved core therein, parts of the core being broken away to show the construction thereof.

Fig. 2 is a transverse section of the core.
Fig. 3 is an end view of one section of the core.

Figs. 4 and 5 are side elevations of the two types of core sections, and

Fig. 6 is a partial, transverse section substantially on the line 6—6 of Fig. 1. I have illustrated my invention as applied to a mold for casting metal tubes in which the outer section is represented by reference numeral 10. In the lower end of this section is inserted the core bit 11 secured in position by means of suitable pins 12 passing through openings in the outer section and the core bit.

The core is made up of a plurality of sections preferably four in number. For casting cylindrical tubes, the outer surfaces of the sections are turned to cylindrical shape when the core is expanded, as shown in full lines in Fig. 2. Each section 13 has a sharp longitudinal edge 14 at one side thereof and the other side is beveled at 15 so that, when the sections are in expanded relation, this bevel rests against the inner side of the sharp edge, as shown. The sections are cast with a plurality of lugs 16 and 17 on the inner walls thereof, each lug being provided with a curved inner edge 18 leading to a recess 19 forming the inside of a hook 20. The diagonally opposite sections are identical but the lugs 16 and 17 on adjacent sections are staggered, as shown, so that the lugs will not interfere with each other. Each section is provided at the op-

posite ends thereof with additional lugs 21 and 22 which are provided with sockets 23 and 24, respectively, to receive suitable pins for retaining the sections in position. For this purpose, I preferably employ two discs 100 25 and 26 one at each end of the sections. These discs are practically identical except for the size of the central opening therein. The disc 25 is shown in plan view in Fig. 6 and is provided with four round openings 27 and four elongated openings 28, the openings 27 being adapted to receive one 105 end of the securing pins 29. The other ends

of the pins are adapted to be inserted in sockets 30 in the core bit 11 and sockets 31 in the runnerbox 32, circular recesses 33 and 34 being formed in the top casting and core bit, respectively, to receive these discs, the securing pins 29 preventing the discs turning in the sockets. The elongated openings 28 are adapted to receive one end of pins 35, the other ends being inserted in sockets 21 and 22 in the ends of the core sections. These pins together with the cam element 36 retain the sections in assembled relation in a manner presently to be described.

The top of the outer section 10 of the mold is provided with a flaring rim 37 providing a top shoulder 38 upon which the runnerbox 32 is mounted preferably by means of supporting pins 39. These pins are reduced at their opposite ends at 40 which are adapted to be inserted in sockets 41 and 42 in the outer section 10 and runnerbox 32, respectively, the enlarged central portion of these pins sustaining the bottom of the runnerbox spaced above the shoulder 38 to provide a sight opening so that the caster may observe the inside of the mold and to provide for the escape of gases therefrom. The runnerbox is provided with a flaring funnel shaped recess 43 from which openings 44 lead vertically, through which the metal poured in the funnel flows to the space 45 between the outer section 10 and the core.

The cam element is preferably provided with four longitudinally extending ribs 46, these ribs extending substantially throughout the entire length of the core and having their outer edges rounded, as shown. One end of this element is reduced at 47 to receive the lower disc 26 and is further reduced below this section and threaded for a nut 48. At the upper end of the ribs a cylindrical portion 49 is provided to receive the disc 25 and above this is an enlarged portion 50 extending through the runnerbox to the top thereof on which is threaded a nut 51 which may be polygonally shaped or provided with sockets 52 to receive a suitable instrument for turning the same to clamp the elements of the core together. The top of this element is also provided with an eye 53 to receive the hook of a hoisting mechanism for withdrawing or transporting the core, or for the insertion of a bar whereby it may be turned to collapse the core.

In assembling the pins 29 are driven into the sockets 30 and 31 in the core bit and runnerbox respectively, with which they have a driving fit. Pins 35 are also driven into sockets 23 and 24 in the ends of the core elements 18, these pins also having a driving fit. The cam element is then inserted through the runnerbox, after which it is inverted. The disc 25 is placed in position on the pins 29 and the cylindrical portion 49

of the cam element, and the core members 13 are then placed in position about the ribs 46 with the pins 35 in the top end thereof inserted in the elongated openings 28 in the disc 25. The disc 26 is now placed on the cylindrical portion 47 of the cam element with the pins 35 extending through the elongated openings 28 therein. The nut 48 is then threaded on the end of the core element clamping the disc 26 in position. The elements of the core and the runnerbox are then clamped together by means of the nut 51. The core bit 11 is now inserted in the end of casing 10 and secured therein by means of the pins 12. The assembled core is then lowered into the mold, the pins 29 entering the circular opening in the disc 26, and the pins 40 entering their respective sockets. The mold is now assembled ready for use.

In operation, the cam element is rotated to the position shown in Fig. 2 and reacts against the curved inner edges 18 of the lugs 16 and 17 to hold the core expanded, the sections taking the positions shown in full line in Fig. 2 and are prevented from separating by the action of the pins 35. As in this position, pressure from the lugs 16 and 17 is against the outer edges of the ribs 46, the sections are securely locked in expanded relation, there being no tendency to rotate the cam element and the exterior surface of the core is one continuous surface. After the casting has been poured and hardened, turning of the cam element 36 counter-clockwise, as viewed in Fig. 2, will move the ribs 46 thereof into recesses 19 and further movement will coat with the hooks 20 to draw the beveled edges of the sections inwardly, the sections moving about the sharp edges 14 as pivots, these edges resting against the inner surface of the casting and the side walls of recesses 33 and 34 in the runnerbox 43 and core bit 11, the sections taking the position shown in dotted lines in Fig. 2, pins 35 allowing this by sliding in the elongated openings 28. The core may now be withdrawn from the casting as it bears thereagainst only along the sharp edges 14 of the sections.

It has been found in actual practice that this mold produces a very homogeneous casting practically free from blow holes and pits, that the core is rigidly held in expanded relation during the casting operation but is easily and positively collapsed when it is desired to remove the same from the casting. In light castings the friction of the sharp edges 14 against the inner surface thereof may be sufficient to lift the casting from the mold when the core is withdrawn, and to prevent this suitable stripping lugs may be provided at the top of the outer section 10 of the mold to engage the top of the casting to prevent withdrawal

thereof. In a heavy casting, however, these lugs are not necessary and I have not, therefore, illustrated them in the drawing.

Although I have shown and described my invention as applied to a mold for casting tubular shapes, the principle of the collapsible feature is not confined thereto as I may use this form of collapsing structure for other purposes particularly in forming a collapsible block for blocking machines. In such machines the block is rotated and the long strips of thin sheet metal, as they come from the rolls, are wound thereon. After the metal is wound the block may be collapsed and the coil of metal then removed therefrom without taking the block from the winding shaft.

Having thus set forth the nature of my invention, what I claim is:

20 1. A collapsible form comprising a plurality of sections, supporting elements at the ends of the sections with which they have pivotal and sliding connection, means for retaining the sections in a given position, and means for moving inwardly one edge of each section about the other edge as a pivot to collapse the form.

2. A collapsible form comprising a plurality of sections with a sharp longitudinal edge at one side and the other side beveled, supporting elements at the ends of the sections with which they are pivotally and slidably connected, means for retaining the sections with one side of the sharp edge of one section resting against the beveled edge of the next adjacent section, and means for moving the beveled edge about the sharp edge as a pivot to collapse the form.

3. A collapsible form comprising a plurality of sections, and a rotatable cam element adapted to hold the form in expanded condition and upon rotation thereof to draw the sections inwardly to collapse the form.

4. A collapsible form comprising a plurality of sections, lugs on the inner walls of said sections provided with a recess, and a rotatable cam element adapted to coact with the lugs to hold the form expanded and adapted upon turning thereof to coact with the recess to draw the sections inwardly to collapse the form.

5. A collapsible form comprising a plurality of sections, lugs on the inner walls of the sections, and a cam element having ribs to engage the lugs and hold the sections in expanded relation, said ribs also adapted on turning of the cam element to coact with the lugs to collapse the form.

6. A collapsible form comprising a plurality of sections, discs at the opposite ends of the sections having elongated openings therein, pins extending in the elongated openings and the ends of the sections, a cam element mounted to turn in the discs, and lugs on the sections coacting with the cam

element to hold the sections expanded and to collapse the form.

7. A collapsible form comprising a plurality of sections, discs at the opposite ends of the sections having elongated openings therein, pins extending in the openings and the ends of the sections, a cam element mounted to turn in the discs and provided with longitudinally extending ribs, and lugs on the sections coacting with the ribs to hold the sections in expanded relation, said ribs also adapted upon turning of the cam element to coact with the lugs to collapse the form.

8. A collapsible core for use in casting tubular shapes, comprising a plurality of sections having a sharp longitudinal edge at one side, a cam element adapted to hold the sections in expanded relation, and means on the sections adapted to coact with the cam element to turn each section about the sharp edge as a pivot to collapse the core.

9. A collapsible core for use in casting tubular shapes, comprising a plurality of sections having a sharp longitudinal edge at one side and beveled at the other side, said bevel adapted when the sections are in expanded relation to contact with one side of the sharp edge of the adjacent section, a cam element adapted to hold the sections in expanded relation, and means on the sections adapted to coact with the cam element to move the beveled edges inwardly about the sharp edges as pivots to collapse the form.

10. A collapsible core for use in casting tubular shapes, comprising a plurality of sections having a sharp longitudinal edge at one side, discs at opposite ends of the sections provided with elongated openings, pins extending into the openings and the ends of the sections, a cam element mounted to turn in the discs, and means on the sections adapted to coact with the cam element to retain the sections in expanded relation and adapted on turning of the cam element to coact with the same to turn the sections about the sharp edges as pivots to collapse the core.

11. A collapsible core for use in casting tubular shapes, comprising a plurality of sections having a sharp longitudinal edge at one side, supporting means at the ends of the sections with which they have pivotal and slideable connection, and means to hold the sections in expanded relation and to turn the sections about the sharp edges as pivots to collapse the core.

12. A mold comprising an outer hollow section, a core bit in one end thereof, a runnerbox spaced from the other end of the section and provided with pouring openings, a collapsible core comprising a plurality of sections, means for securing the ends of the sections to the core bit and runnerbox, and

means for holding the sections in expanded relation and for moving the same to collapsed relation.

13. A mold for casting tubular shapes comprising an outer hollow section, a core bit in one end thereof, a runnerbox spaced from the opposite end thereof and provided with pouring openings, a collapsible core comprising a plurality of sections each having a sharp longitudinal edge at one side thereof and its ends having pivotal and slideable connection with the core bit and runnerbox, and means for holding the sections in expanded relation and for turning the sections about the sharp edges as pivots to collapse the core.

14. A mold for casting tubular shapes comprising an outer hollow section, a core bit in one end thereof, a runnerbox spaced from the opposite end thereof and provided with pouring openings, a collapsible core comprising a plurality of sections, discs mounted in the core bit and runnerbox, means for securing the ends of the sections to the discs, and means mounted to turn in the discs to hold the sections in expanded relation and move the same to collapsed relation.

15. A collapsible form comprising a plurality of sections, discs at the opposite ends of the sections having elongated openings therein, pins extending in the elongated openings and the ends of the sections, a cam element mounted to turn in the discs, and lugs on the sections coacting with the cam element to hold the sections expanded.

16. A collapsible form comprising a plurality of sections, discs at the opposite ends of the sections having elongated openings therein, pins extending in the openings and the ends of the sections, a cam element mounted to turn in the discs and provided with longitudinally extending ribs, and lugs on the sections coacting with the ribs to hold the sections in expanded relation.

17. A collapsible core for use in casting tubular shapes, comprising a plurality of sections having a sharp longitudinal edge at one side, discs at opposite ends of the sections provided with elongated openings,

pins extending into the openings and the ends of the sections, a cam element mounted to turn in the discs, and means on the sections adapted to coact with the cam element to retain the sections in expanded relation.

18. A mold for casting tubular shapes comprising an outer hollow section, a core bit in one end thereof, a runnerbox spaced from the opposite end thereof and provided with pouring openings, a collapsible core comprising a plurality of sections, discs mounted in the core bit and runnerbox, means for securing the ends of the sections to the discs, and means mounted to turn in the discs to hold the sections in expanded relation.

19. A collapsible form comprising a plurality of sections, supporting elements at the ends of the sections, means for pivotally and slidably connecting the sections to said supporting elements, a cam element comprising a bar mounted to rotate in the supporting elements and having longitudinally spaced stop means to position the supporting elements thereon, said cam element and sections having coacting surfaces whereby the sections may be moved to expanded position, means on the bar for securing the elements in assembled relation, and means whereby the bar may be rotated.

20. A collapsible form comprising a plurality of sections having a sharp longitudinal edge at one side, supporting elements at the ends of the sections, means for pivotally and slidably connecting the sections to said supporting elements, a cam element comprising a bar mounted to rotate in the supporting elements and having longitudinally spaced stop means to position the supporting elements thereon, said cam element and sections having coacting surfaces adapted on rotation of the cam element to move the sections to expanded position or turn the sections about the sharp edges as pivots to collapse the form, means on the bar for securing the elements in assembled relation, and means whereby the bar may be rotated.

In testimony whereof I affix my signature,
GEORGE E. BRONSON.
